UNITED STATES PATENT OFFICE.

FREDERICK W. C. NEUNER, OF CONNERSVILLE, INDIANA, ASSIGNOR TO INDIANA LAMP CORPORATION, OF CONNERSVILLE, INDIANA.

REFLECTOR-SUPPORTED LIGHT-SOCKET MOUNTING.

Application filed April 15, 1927. Serial No. 184,001.

This invention relates to head lamps and particularly to the mounting of the light bulb support upon the reflector.

- The chief object of the invention is to 5 detachably but relatively rigidly mount a light bulb supporting socket upon a reflector and in a predetermined position so that a predetermined relation will always be obtained between the reflector and the bulb focus.
- 10 The chief feature of the invention consists in the provision of a light bulb supporting plug socket and detachably but rigidly mounting the same upon a reflector in a predetermined position thru a yielding inter-
- 15 lock.

The full nature of this invention will be understood from the accompanying drawings and the following description and claim.

- Fig. 1 is an elevational view of a proportion 20 of a reflector plug socket support and plug socket associated therewith. Fig. 2 is a longitudinal sectional view taken on line 2—2 in the direction of arrows. Fig. 3 is an end or rear view.

- 25 In the drawings 10 indicates a reflector having a central aperture 11. A tubular sleeve 12 having a plural flange portion 13 is positioned in the reflector aperture whereby the sleeve is permanently and rigidly anchored to the reflector. Slidably receivable by the sleeve is a light bulb supporting plug socket 14 having the J slots 15 which detachably receive the anchoring bayonet pins 16 of a light bulb base 17 positionable in the plug socket and supporting the light bulb 18 with the filament 19.

- Inasmuch as the filament of the lamp bulb bears a definite relation to the focus of the reflector with respect to the character of the 40 beam projected thereby, it is essential that the plug socket 14 be positioned in predetermined relation relative to the reflector. The plug socket includes a relatively closed rear end 20 having the aperture 21 therein to permit the entrance of the current conducting wires to the plug contact not shown. To positively position the socket as aforesaid, said socket is supplied with a plurality of notches or slots 22, a pair being shown and diametri- 45 cally arranged. The sleeve 12 is split or

slotted at 23 to provide a spring tongue 24 which has an angular tooth 25 formed on the end thereof and receivable by a slot or recess 22 in the plug socket.

This construction permits the convenient 55 detachment of the plug socket from the reflector by manually actuating one of the springs 24 and 124, but fixedly secures a relatively rigid mounting thereof and the positive positioning of the socket and reflector 60 in predetermined relation. Thru the formation of a second tooth 125 (reversely formed from that shown at 25) upon another tongue 124, forward movement of a plug socket in the sleeve is prevented by the tongue 124 65 since the wall of the slot 22 engages the tooth 125. Rearward movement of the socket is prevented by the tooth 25 of tongue 24 seating in the opposite slot 22 in the plug socket. The foregoing arrangement also prevents 70 rotative movement between the socket and sleeve but permits forcible removal of the socket if the same is desired.

The invention claimed is:

In a lamp structure, the combination with 75 a reflector and a bulb having a filament, of means for removably supporting said bulb in fixed relation in respect to said reflector including a tubular sleeve having a double flanged head extending into and centrally of 80 the reflector, said double flanged head adapted to embrace the adjacent portion of the reflector so as to securely unite said reflector and sleeve, a pair of oppositely disposed spring arms stamped out from the body of 85 said sleeve and provided with latching teeth on the free ends thereof, and a bulb receiving socket extending through said sleeve, the body of said socket being provided with 90 openings for receiving said teeth and causing the same to interlock said socket and sleeve, said latching teeth being arranged oppositely to each other whereby one of said teeth will prevent longitudinal movement between the sleeve and socket in one direction and the 95 other tooth will prevent movement in the opposite direction.

In witness whereof, I have hereunto affixed my signature.

FREDERICK W. C. NEUNER.
